MACHINE FOR WINDING YARN AND THE
LIKECharles Marsden, Ahmedabad, Bombay, British
IndiaApplication May 25, 1936, Serial No. 81,742
In Great Britain June 18, 1935

2 Claims. (Cl. 242—31)

This invention is for improvements in or relating to machines for winding yarn and the like in conical chases. One object of the invention is to provide an efficient transmission of the drive to the traversing means. Another object is to increase the speed of operation attainable in such machines by reducing frictional losses and reducing the number of moving parts required.

According to the present invention there is provided a machine which comprises the combination with a winding spindle, a worm mounted on the winding spindle to rotate with the latter, a thread-guide between which and the winding spindle relative reciprocation takes place to traverse the yarn or the like longitudinally of the winding spindle, and means for effecting a step-by-step relative displacement between the thread-guide and the winding spindle longitudinally of the latter in accordance with the growth of the package, of a worm-wheel which engages and is driven by the said worm and is itself formed with a cam-track serving to effect the said relative reciprocation between the thread-guide and the winding spindle. Thus, in accordance with the invention a single member serves both as the gear by which the cam is driven and as the cam itself. This has the advantages of reducing the number and size of the bearings required and reducing the number of moving parts needed, with the result that high speeds of operation are attainable. Preferably, the said cam-track is afforded by a double-sided groove formed in a face of the worm-wheel.

In one construction according to the invention there is a bellcrank lever whereof one arm carries a follower engaging the said cam-track and the other arm is coupled to a reciprocating member which, when operated by the arm, causes the said relative reciprocation to take place between the thread-guide and the winding spindle.

A preferred form of winding machine in accordance with the invention will now be described by way of example only and with reference to the accompanying drawings.

In the drawings,

Figures 1a and 1b show the winding machine in plan view with certain parts omitted;

Figure 2 is an elevation partly in section of the parts shown in Figure 1a, and

Figure 3 is a cross-sectional view of the worm-wheel and its mounting taken on the line 3—3 of Figure 1a.

Like reference numerals indicate like parts throughout the drawings.

As shown in the drawings, the machine com-

prises a main frame 10 having bearings 11 for a tubular clutch-member 12 and a spindle 13 which lies within it. The tube 12 carries a grooved wheel 14 which abuts against a spring 15, the other end of which engages a collar 16 affixed to the spindle 13. The worm 17 forms part of a tube which is also affixed to the spindle 13.

Rotatably mounted on the left-hand end of the spindle 13 is a pulley 19 having a conical face to cooperate with a clutch-member 20 formed integrally with the tube 12. The outer end of the spindle 13 is supported in a bracket 21.

The right-hand end of the tube 12 is formed with dogs 22 adapted to engage with corresponding slots in the collar 16 whereby a driving connection is established between the tube 12 and the collar 16 so that when the clutch-member 20 is in frictional engagement with the pulley 19 rotation of the pulley drives the spindle 13.

The right-hand end of the spindle carries spring-fingers 23 to engage the end 24 of a cop-holder, the other end 25 of the cop-holder being supported by a centering spindle 26 mounted in bearings in a plunger 27 pressed towards the cop by means of a spring 28 and slideable in a guide 29. The plunger 27 terminates in a knob 30 whereby it may be retracted manually.

The worm 17 (see Figures 2 and 3) engages and drives a worm-wheel 31 which rotates on an anti-friction bearing 80 carried on a post 81 secured to the frame 10 by a bolt 82. The bearing 80 is mounted on a reduced portion 83 of the post 81 and is secured in place by a nut 84 between which and the inner race of the bearing 80 there is interposed a spacer 85 and the loop of a spring anchorage 86. The latter has secured to it one end of a spring 69 associated with the stop-motion of the machine. The worm-wheel 31 has cut in its face a double-sided cam-track comprising two portions 32 and 33. The track is engaged by a follower 34 on the shorter arm 35 of a bell crank lever 35, 36 pivoted to the frame at 37. The arm 36 is pivoted to a link 38 which is in turn pivoted at 39 to a traverse-rod 40 slideable in a tubular guide 41 and in a bush 42. It will be seen from reference to Figure 1a that the bellcrank lever 35, 36 is so mounted that its two arms and its pivot are, as viewed in plan, mounted between the winding spindle 13 and the traverse-rod 40.

The traverse-rod 40 carries a screwthreaded extension 43 on which a progression wheel 58 having a hub 59 is mounted. The hub 59 is straddled by a stirrup 61 which is also mounted on the rod 43 and carries the thread-guide shown at 62.

The screwthreaded rod 43 is coupled to the traverse-rod 40 by a pin 48 engaging in a slot 47 in a former bar 46 screwed to the end of the traverse-rod and secured in place by a lock-nut 45. The 5 former bar 46 fits in a slot in the screwthreaded rod 43 and is adapted to engage the interior of the hub 59 of the progression wheel 58 at the commencement of the winding operation to build the "heel" on the cop. The outer end of the 10 screwthreaded rod 43 is mounted in a universal joint 54 in a sleeve 55 attached to a bracket 57 secured to the main frame 10.

At the commencement of the winding operation the progression wheel 58 is moved to the left as 15 seen in Figure 1b and the interior of its hub engages the former bar 46 as described in my co-pending application Serial No. 33,187, filed 25th July, 1935. This causes the rod 43 to be rocked about the universal joint 54 to bring the periphery of the progression wheel 58 adjacent to the 20 yarn support. As the first few layers of yarn are wound on the yarn support the progression wheel is rotated by contact therewith and moved progressively to the right as viewed in Figure 1b. 25 This permits the rod 43 to move in steps back to the position shown in Figure 1b as the "heel" of the cop is formed. Thereafter the yarn is wound in conical chases to produce a cylindrical or approximately cylindrical package with tapered 30 ends.

In the machine shown in the drawings the two parts 32, 33 of the traverse-cam groove are of different lengths and are somewhat steeper than an archimedean spiral as described in my co-pending application Serial No. 81,741 of even date herewith. Also the former bar 46 has its profile 35 slightly concave.

When the cop has been fully built the progression wheel 58 operates suitable devices to release the cone 20 from the pulley 19 and thereby 40 interrupt the drive.

In the method of operation described above the former bar 46 and screwthreaded rod 43 are initially set so that when the "heel" has been 45 formed the rod 43 will lie coaxial with the traverse-rod 40. However, the parts may be differently arranged to give any desired shape to the "heel" of the cop. The parts may also be arranged to wind on to a pirn having a preformed 50 conical end on which the yarn is laid in conical chases. For this purpose the spindle 13 may be movable to the right as seen in Figures 1a and 1b relatively to the tube 12, collar 16 and worm 17, this being permitted by the release of appropriate grub-screws which are subsequently 55 retightened. Such movement of the winding spindle is made with the object of commencing the winding operation with the hub 59 of the progression wheel out of co-operation with the former bar 46. Alternatively, for winding on to a cone-ended pirn it may be feasible in some 60 circumstances to turn the former bar about the traverse-rod axis to a sufficient angular extent to prevent it from moving the progression wheel 58 towards the winding spindle. In this case it will 65 be unnecessary to move the spindle 13.

By having the worm-wheel 31 and traverse rod formed as a single member an efficient drive is secured. The number or length of the bearings is reduced, as well as the number of moving parts. There is also the advantage that the 5 thrust from the worm 17 for operating the traverse rod 40 is transmitted through the material of the wheel itself and not through its bearing. The grooved form of cam also provides for positive control of the traverse rod in both directions 10 of its movement. The general result of all these advantages is that the machine can be operated at high speeds such as have not previously been attained in the class of winding machines with which the invention is concerned. 15

It is to be understood that the invention is not restricted to the precise constructional details shown in the drawings.

I claim:

1. In a machine for winding strand material in 20 conical chases, the combination comprising a winding spindle, a worm mounted on the winding spindle to rotate with the latter, a traverse-rod, a thread-guide adapted to be reciprocated by the traverse-rod to traverse the strand material 25 longitudinally of the winding spindle, a progression wheel carried by the traverse-rod for effecting a step-by-step relative displacement between the thread-guide and the winding spindle longitudinally of the latter in accordance with the 30 growth of the package, a worm wheel which engages and is driven by the said worm, a slow-speed traverse-cam formed directly in a face of the worm wheel itself, a bell-crank lever pivoted to rock about an axis parallel to the axis of the worm 35 wheel, a follower mounted on one arm of the bellcrank lever and engaging the cam-track of the worm wheel, and means coupling the other arm of the bellcrank lever to the said traverse-rod. 40

2. In a machine for winding strand material in conical chases, the combination comprising a winding spindle, a worm mounted on the winding spindle to rotate with the latter, a traverse-rod, a thread-guide adapted to be reciprocated by the 45 traverse-rod to traverse the strand material longitudinally of the winding spindle, a progression wheel carried by the traverse-rod for effecting a step-by-step relative displacement between the thread-guide and the winding spindle longitudinally of the latter in accordance with the growth 50 of the package, a worm wheel which engages and is driven by the said worm and is itself formed with a cam-track for effecting a close-wind traverse, a bellcrank lever having its arms and pivot 55 lying, as viewed in plan, between the said traverse-rod and the winding spindle, a pivotal mounting for said bellcrank lever adapting it to rock about an axis parallel to the axis of the worm wheel, a follower mounted on one arm of the 60 bellcrank lever and engaging the cam-track of the worm wheel, and means coupling the other arm of the bellcrank lever to the said traverse-rod. 65

CHARLES MARSDEN. 65
